UNITED STATES PATENT OFFICE.

CHARLES ALVAH SMITH, OF BRATTLEBORO, VERMONT.

BORING-MACHINE.

1,394,766.

Specification of Letters Patent.

Patented Oct. 25, 1921.

Application filed July 15, 1919. Serial No. 310,923.

To all whom it may concern:

Be it known that I, CHARLES A. SMITH, a citizen of the United States, and a resident of Brattleboro, in the county of Windham and State of Vermont, have invented certain new and useful Improvements in Boring-Machines, of which the following is a specification.

This invention relates to boring machines 10 of the multi-drill type.

An important object of the invention is to provide a boring machine having novel means whereby the vertical and horizontal drills may be simultaneously fed to the work 15 for drilling the hole at different angles into the work.

The invention forming the subject matter 20 of this application is also provided with novel means whereby the pieces to be operated upon are fed to and held in position while being drilled.

In the accompanying drawings, forming a 25 part of this application and in which like numerals are employed to designate like parts throughout the same—

Figure 1 is a front elevation of the improved boring machine.

Fig. 2 is a vertical sectional view through the same.

Fig. 3 is a side elevational view, the view 30 being taken from the opposite side of the machine, a driving pulley 57 being shown on the opposite side of the machine from that shown in Figs. 1, 4 and 5.

Fig. 4 is a fragmentary front elevation of 35 the machine, the magazine being omitted for the purpose of clearness.

Fig. 5 is a rear elevation illustrating the operative means for the machine.

Fig. 6 is a side view illustrating the operating means for the machine, driving pulley 57 being shown as in Fig. 3.

In the drawings wherein for the purpose 45 of illustration is shown a preferred embodiment of the invention, the numeral 10 generally designates the frame which consists of four spaced parallel uprights 11 and upper and lower cross pieces 12 and 13 respectively. The cross pieces 12 which extend 50 from the front to the rear of the frame are joined intermediate their ends by a connecting cross piece 14. The rear ends of the cross pieces 12 are connected by a transversely extending strip 15.

55 As illustrated in Figs. 1 and 2 a vertical shaft 16 is rotatably connected to one of the

uprights 11 by means of a pair of bearing brackets 17 which are formed with alined apertured ears which rotatably receive the shaft. A triangular bracket 18 is rigidly secured on the upper portion of the shaft 16 and supports a table generally designated by the numeral 20 for swinging movement about the axis of the shaft 16. The table generally designated by the numeral 20 may be securely held in position directly in front of the frame by means of a locking device designated by the numeral 21. When the locking device 21 is released, the table 20 may be swung about the longitudinal axis 70 of the shaft. The table 20 may be adjusted vertically by means of an adjusting screw 23 arranged in longitudinal alinement with the shaft 16 and threaded through an ear 24 rigidly secured to one of the uprights 11. 75 The adjusting screw 23 may be manually rotated by means of a wheel 25 and may be secured in an adjusted position by means of a lock nut 26. The upper end of the adjusting screw 23 is provided with anti-friction elements 27 engaged with the lower end of the shaft 16 so that the shaft 16 may rotate independently of the adjusting screw 23.

A movable platform 29 is mounted upon the 80 table 20 and is provided with a plurality of superposed blocks 30 which are as illustrated in Fig. 2 arranged to form a seat for strips of wood 31 which are singly discharged from a magazine generally designated by the numeral 32. It will be observed that the uppermost block 30 has one longitudinal edge portion spaced from the adjacent longitudinal edge portion of the intermediate block so as to define a seat for snugly receiving the 85 strip 31 as it is discharged from the magazine. When the movable platform 29 moves to its advanced position, a piece of work is mounted upon a seat defined by the uppermost and intermediate blocks and is carried 90 to a position where it may be provided with holes by the drilling mechanism to be later described.

When the platform 29 is in its advanced position it retains the remaining pieces of 105 wood 31 within the magazine since the blocks 30 move directly beneath the open lower end of the magazine. A dove-tailed connection may be provided between the movable platform 29 and the table 20 so that 110 the movable platform will move in a straight path.

The movable platform is moved back and forth in the proper order by means of a link 35 which has its upper end portion threaded through a nut 36 carried by a bracket 37 depending from the extended portion of the platform. The lower or rear end portion of the link 35 is pivoted to the terminal portion of a crank 38 formed at one end of the shaft 39. When the shaft 39 is rocked the crank 38 will of course be moved for imparting a back and forth movement to the link 35. As the link 35 is moved back and forth the platform 29 is reciprocated for delivering the pieces of work 31 to a position where they may be drilled. By rotating the link 35 within the nut 36, it is possible to vary the effectiveness of the link 35 for regulating the reciprocation of the platform.

The shaft 39 is rotatably supported by means of struts 40 which join the upper and lower sections of the table. The means for rocking the shaft 39 includes a chain 41 which is trained about a pulley 42 keyed or otherwise secured to the extended end portion of the shaft 39. When an upward pull is exerted on a link 43 connected to the upper end of the chain 41 the wheel 42 and consequently the shaft 39 will be rotated to a limited degree whereby the platform will be moved across the table to its operative position or to a position where the work may be operated upon.

As illustrated in Fig. 3, the upper end of the link 43 is connected to a radial arm 44 rigidly secured to a rock shaft 45. The rock shaft 45 is rotatably supported by bearings 46 which are mounted upon the cross beam 14. When the rock shaft 45 is rotated the arm 44 will be elevated for imparting a corresponding movement to the link 43. As the lower end of the chain 41 is connected to the wheel 42, the wheel and consequently the shaft 39 will be rotated to a limited degree.

A second arm 47 is secured on the shaft 45 in connection with a link 48 which is joined with the terminal portion of a crank arm 49 secured on a rock shaft 50. The rock shaft 50 is rotated by means of a second crank arm 51 which has a roller 52 in contact with a cam 53. The cam 53 is rigidly secured on a shaft 54 and when the cam is rotated, through the rotation of the shaft 54, the lobe on the same will engage the roller 52 and thereby move the radial arm 51 downwardly. This downward movement thus imparted to the crank arm 51 will rock the shaft 50 and thereby cause the arm 49 to be moved downwardly for imparting a corresponding movement to the link 48. Therefore, when the shaft 54 is rotated, the lobe on the cam 53 will operate the bell crank formed by the arms 49 and 51 for rocking the other bell crank formed by the arms 44 and 47. The operation of the

upper bell crank formed by the arms 44 and 47 will elevate the link 43 for imparting a sliding motion to the platform 29.

With reference to Fig. 5 it will be observed that the shaft 54 on which the cam 53 is arranged has connection at one end with a train of gears 55. The shaft 56 which is connected to the gears 55 is provided with a pulley 57 which has connection with a belt 58. The belt 58 is trained about a conical pulley 59 on a shaft 60 which is driven by means of a belt trained about a pulley 61.

The magazine which is generally designated by the numeral 32 is carried by a pair of frames 63 which are secured to the lower ends of hangers 64. These hangers 64 have pivoted to their lower ends bars 64' and the frames 63 have slotted flanges each clamped by a thumb screw to said bars 64'. The magazine 32 may be adjusted vertically by means of adjusting screws 65 which contact with ears 66 projecting from the ends of the slotted flanges of the frames. The lower portions of the adjusting screws 65 are threaded through ears or lugs 67 rigidly connected with the ends of the bars 64'.

As previously stated, when the platform 29 is in its retracted or rear position, one piece of work 31 drops from the magazine onto the seat formed by the upper and intermediate blocks 30 and said seat is advanced to a point beneath the horizontal portions of stop arms 68. The stop arms 68 which properly position the pieces of work are adjustable transversely of a set up bar 69 which extends transversely of the frame. The set up bar 69 is adjustable with relation to the magazine by means of bolts 70 which extend through stationary blocks 71. The horizontal portions of the stop arms 68 overhang the pieces of work and also the uppermost blocks 30 so that the pieces of work are securely held in a position to be operated upon by the several drills.

The drilling mechanism includes a pair of spaced parallel vertically arranged guide rods 70' which are secured at their upper ends to brackets 71' connected to the cross piece 14 and at their lower ends to brackets 72 secured to the uprights 11. The guide rods 70' slidably support a vertically movable carriage designated by the numeral 73. The ends of the carriage 73 are provided with vertically aligned bearings 74 which slidably receive the rods 70' whereby the carriage may move upwardly and downwardly during the operation of the machine.

As illustrated in Figs. 2 and 3, a yoke 76 is arranged in front of the carriage and is adjustably connected to the same by means of a bolt 77 which passes through a slot 78 in the carriage. With reference to Fig. 1 it will be observed that the bracket 76 may be adjusted transversely of the carriage so that a chuck 79 mounted on a spindle 80

may be engaged with the work at any desired point. The spindle 80 is rotatable within alined bearings 81 and is provided at its upper end with a wheel 82. The wheel 82 is gradually thickened toward its medial portion and has a belt 84 connected thereto, which belt is trained about a drum 85. The drum 85 is provided at one end with a pulley 86 about which a belt 87 is trained. 5 As illustrated in Fig. 5 the belt 87 which is continuous is trained about the wheel on the shaft 60. As further illustrated in Fig. 5, the member 85 is in the nature of a drum and extends entirely across the frame so that 10 the belt 84 will move transversely on the drum 85 when the spindle is moved transversely of the frame. In this manner, the belt 84 extends in a straight line behind the drill. The drill is carried by the chuck 79 15 so that as the carriage 73 is lowered a hole will be drilled in the work.

In operation the carriage is raised and lowered by means of a link 90 which is connected at its upper end to a crank arm 91 20 having a longitudinal slot 92 for the reception of a block 93 which is adjustable in the slot to determine the throw given by arm 91. The block is provided with a pivot element 94 which is connected to the link 90 so that 25 30 as the arm 91 is moved upwardly, the link will not be distorted and will be elevated. The effective length of the link 90 may be varied by means of an adjusting nut 95 which is threaded on the upper end of the link 90. The slotted arm 91 is secured on a rock shaft 96 which is rotatably carried by the bearings 97 which are secured onto the cross piece 14 in the manner illustrated. A second crank arm 98 is secured on the 35 40 rock shaft 96 and has connection with a link 99 which extends downwardly and is pivotally connected to the terminal portion of a crank arm 100. The crank arm 100 has rigid connection with a shaft 101 rotatably carried by a bearing bracket 102. A second crank arm 103 is rigidly secured on the rock shaft 101 and has its end provided with a roller 104 arranged in the path of travel of a lobe formed on a cam 105. The 45 50 cam 105 is rigidly secured on the shaft 54 and serves as a means for moving the crank arm 103 downwardly at intervals, whereby the link 99 will be periodically drawn downwardly. This downward movement thus 55 60 imparted to the link 99 elevates the arm 91 for moving the same upwardly so that a vertical upward movement will be imparted to the carriage 73. The weight of the carriage 73 and the spindle is greater than the link 99. 65 When the lobe on the cam 105 passes the roller 104, the carriage 73 is free to move downwardly so that the drill carried by the chuck will enter the wood.

A second carriage 110 is arranged horizontally and is provided with bearings 111

which are slidable upon a pair of horizontally arranged guide rods 112. The guide rods 112 which are stationary are mounted upon brackets 112'. As illustrated in Fig. 2, a yoke 113 similar in construction to the 70 yoke 76 is mounted on a horizontal carriage 110 and is provided with a spindle 114 which carries a chuck 115. The chuck of course carries the usual drill for engaging the work. A pulley wheel 116 is secured on the 75 spindle 114 and has connection with a belt 117 trained about a drum 118. The drum 118 extends entirely across the lower portion of the frame and has connection with a belt 119. The belt 119 has connection with the shaft 60 through the medium of a pulley wheel 120.

The spindle 114 moves longitudinally as well as rotatably and the longitudinal movement of the spindle is of course accompanied by a slight stretching of the belt 117. The means employed for reciprocating the horizontal carriage 110 includes a slotted arm 120 which is connected to the rock shaft 101. The slotted arm 120 receives a block 121 to 90 which a link 122 is connected. The forward portion of the link 122 has pivotal connection with the rear portion of the carriage 110.

In the operation of the improved boring 95 machine, the pieces of work are fed singly from the magazine onto the seat formed by the block 30. The seat formed by the block 30 of course receives the lowermost piece of work when the platform is in its retracted position. As the platform advances in the direction of the horizontal drill, it carries with it a piece of work which is moved beneath the horizontal portions of the stop arm 68. When the platform reaches its 100 advanced position, the work is securely held in place and the vertical and horizontal drills advance and thereby provide the piece of work with holes. Upon the completion of the boring operation, the drills are withdrawn through the rearward movement of the vertical and horizontal carriages. The cam 53 of course is the means by which the platform is slidably moved and when the lobe on this cam passes the roller 52, a 105 coiled spring 130 mounted on the shaft 39 returns the platform to its retracted position.

The vertical and horizontal carriages are of course timed so as to feed the drills to the 110 work at the proper time during the operation of the machine.

Having thus described the invention what is claimed is:—

1. A boring machine comprising a tool 125 supporting frame, a table swingingly connected at one end to said tool supporting frame for movement about a vertical axis to and from the same, a reciprocating platform mounted on said table, and a platform re- 130

- ciprocating device mounted in part on said table and in part on said frame and having means whereby the same is operative regardless of the position of said table.
5. A boring machine comprising a tool supporting frame, a table swingingly connected at one end to said tool supporting frame for movement about a vertical axis to and from the same, a reciprocating platform 10 mounted on said table, a platform reciprocating device mounted in part on said table and in part on said frame and having means whereby the same is operative regardless of the position of said table, and a magazine 15 carried by said frame above said platform.
3. A boring machine comprising a tool supporting frame, a table swingingly connected at one end to said tool supporting frame for movement about a vertical axis to 20 and from the same, a reciprocating platform mounted on said table, a platform reciprocating device mounted in part on said table and in part on said frame and having means whereby the same is operative regardless of 25 the position of said table, a magazine carried by said frame above said platform, and a locking device for one end of said table.
4. A boring machine comprising a tool supporting frame, a magazine supported by 30 said frame, a table swingingly connected to said frame and having means for feeding blanks from said magazine and mounted to swing laterally with said feeding means from beneath said magazine.
- 35 5. A boring machine comprising a tool supporting frame, a magazine supported by said frame, a table swingingly connected to said frame and having means for feeding blanks from said magazine and mounted to swing laterally with said feeding means from beneath said magazine.
- supporting frame, a magazine supported by said frame, a table swingingly connected to said frame and having means for feeding blanks from said magazine and mounted to swing laterally with said feeding means 40 from beneath said magazine, and a drilling mechanism carried by said frame.
6. A boring machine comprising a frame, a table carried thereby and swingable on a vertical axis away from said frame, a shaft 45 rotatably carried by the table, a platform movable on the table, means connecting the shaft and the platform, means to rock the shaft in one direction comprising a flexible connection to a moving part of the frame, 50 permitting the swinging of the table without affecting the operation of the shaft rocking means, and a spring associated with the shaft for rocking the same in the opposite direction.
7. A boring machine comprising a frame, a table carried thereby and swingable on a vertical axis away from said frame, a shaft carried by said table, a platform mounted for sliding movement on the table, a link 55 connected to said platform, a crank connected to said shaft and to said link, means for rocking said shaft in one direction comprising a flexible connection to a movable part on the frame, permitting the swinging 60 of the table without affecting the operation of the shaft rocking means, and a spring for returning the platform to its retracted position.

CHARLES ALVAH SMITH.
